DESIGN FOR A TOWEL, NAPKIN HOLDER, OR THE LIKE

John Thompson, Albany, N. Y., assignor to
A. P. W. Products Company, Inc., Albany, N. Y., a corporation of New York

Application June 25, 1947, Serial No. 139,908

Term of patent 14 years

(Cl. D44—24)

To all whom it may concern:

Be it known that I, John Thompson, a citizen of the United States of America, residing in Albany, county of Albany, State of New York, have invented a new, original, and ornamental Design for a Towel, Napkin Holder, or the like, of which the following is a specification, reference being had to the accompanying drawing, forming part thereof, wherein:

Fig. 1 is a top view of a towel, napkin holder, or the like, showing my new design.

Fig. 2 is a front elevation of the holder shown in Fig. 1.

Fig. 3 is a side elevation of the holder shown in Fig. 1.

Fig. 4 is a section taken along the plane of the line 4—4 of Fig. 2.

I claim:

The ornamental design for a towel, napkin holder, or the like, as shown.

JOHN THOMPSON.
